UNITED STATES PATENT OFFICE.

WILLIAM E. SMITH, OF MILLTOWN, NEW JERSEY, ASSIGNOR TO GULBENKIAN SEAM-LESS RUG COMPANY, OF NEW BRUNSWICK, NEW JERSEY, A CORPORATION OF NEW JERSEY.

WIRE-CARRIAGE-RELEASE DOG FOR PILE-WIRE-CONTROLLING MECHANISM FOR LOOMS.

Application filed May 22, 1926. Serial No. 111,020.

My invention relates to improvements in pile wire controlling apparatus for looms, such as illustrated in my co-pending application for U. S. Letters Patent, filed January 5 27, 1925, Serial No. 5,041, and more particularly to the release mechanism of the reciprocating pile wire controlling carriage thereof.

In mechanism of the character above 10 noted, the carriage thereof is adapted to be reciprocated upon a rail, and thereby successively withdraw a pile wire from the fabric which has been woven on the loom, and reinsert the withdrawn pile wire into the 15 open warp shed of the fabric being woven. The withdrawing cycle of the reciprocation of the carriage is effected by means of a chain and mechanism on the carriage adapted to be engaged by a projection on the 20 chain, the said mechanism being adapted to be released from engagement with the chain when the said carriage reaches its extreme outward position.

Under ordinary conditions, prior to the 25 conception of my invention, a fixed projection was employed and secured to the rail, and adapted to engage mechanism on the carriage to effect its release from the driving chain. The carriage, during its recip- 30 rocation, moves at a high rate of speed, and when released from the driving chain the momentum developed in its outward movement causes the carriage to strike the fixed abutment with considerable force resulting 35 in damage to the elements of the carriage, after a period of continuous use, and therefore requires considerable attention in order that the mechanism may be maintained in an operable condition.

The principal objects of my invention are 40 to provide mechanisms for releasing the carriage from the drive chain, for dampening the momentum developed in the outward movement of the carriage, for finally arresting 45 such movement, stopping the carriage and preventing it from contacting with the fixed abutment on the rail.

Details of my invention will be described 50 more fully hereinafter, reference being had to the accompanying drawings, of which:

Fig. 1 is a plan view of sufficient of the

wire controlling mechanism to illustrate my invention;

Fig. 2 is a sectional elevation taken along the line 2—2 of Fig. 1, and showing the 55 wire controlling carriage in a position approaching the fixed releasing element therefor;

Fig. 3 is a view similar to Fig. 2 illustrating the carriage as initially engaging 60 the fixed releasing element, shown in full lines, and in the final arresting position shown in broken lines, and

Figs. 4 and 5 respectively illustrate a plan and side elevation of a modified form of my 65 invention.

Referring to Figs. 1, 2 and 3 of the drawing, the wire controlling carriage is illustrated at 1, having a body portion 2 adapted to a rail 3. The wire controlling carriage 1 is provided with a hook 4 adapted to engage the head 5 of a pile wire 6 in the usual manner. The rail 3 is provided with the usual groove 7 for the accommodation and to permit movement of the driving chain 8 which is adapted to move the carriage outward in the direction of the arrow shown in Fig. 2. Movement of the carriage in the opposite direction may be effected by any suitable means, and as illustrated in the accompanying drawings a chain 9 is provided for the purpose and is adapted to engage a latch 10 on the carriage, as fully described in the above mentioned co-pending application, this mechanism forming no part of the present invention.

The drive chain 8 is provided with a projection 11 adapted to be engaged by a shoulder 12 forming part of a drive latch 13 pivoted at 14 to a pair of vertical projections 15, 15 on the carriage 1. A retaining lever 16 is pivoted at 17 to the brackets 15, 15 of the carriage 1 and is provided with a suitably shaped end 18 adapted to co-operate with a similarly formed cavity 19 in the driving latch 13, as illustrated in Fig. 2, the retaining lever 16 being adapted to engage the drive latch 13 and retain the shoulder 12 thereof in operative engagement with the projection 11 of the drive chain 8.

In accordance with the principles of my invention, the retaining lever 16 has inte-

grally formed therewith a release dog 20 having a pin 21 projecting laterally therefrom, and adapted to receive one end of a tension spring 22, the opposite end of which is secured in any suitable manner to the carriage 1, in the present instance an eye 23 suitably secured therein.

The release dog 20 is of an arcuate form, and comprises a cam path 24 adapted to be engaged by a projection on the rail 3, which in the present instance, comprises a roller 25 rotatably mounted on a stud 26 which is adjustably mounted in a slot formed in an arm 27 projecting from an abutment element 28.

15 The abutment element 28 comprises a body portion 29 suitably aperture to receive a pair of retaining bolts 30. Each of the retaining bolts 30 is provided with a rectangular head 31 adapted to lie within the chain groove 7 of the rail 3, and to engage the upper overhanging wall 32 of a groove 33 formed in each of the side walls of the rail 3 and in which the body portion 2 of the carriage slides. Each bolt 30 is provided with a 20 clamp nut 34 by means of which the head 31 of the bolt is drawn tightly against the projecting surface 32 of the rail, thereby clamping and rigidly securing the abutment element 28 in a fixed position on the upper 25 face of the rail 3.

In Figs. 4 and 5 of the drawing, I have illustrated a modified form of the invention wherein the retaining lever 16^a is rigidly secured to and intermediate the ends of a 30 shaft 35, which is pivotally mounted in bearings 36 formed on the projections 15, 15 of the carriage 1.

Secured to one end of the shaft 35 is the release dog 20^a which is adapted to engage a 40 cam face 37 formed on a projection 27^a adjustably secured to one side of the rail 3. Upon the end of the shaft 35, opposite the release dog 20^a, is secured a lever 38, and adjustably mounted in the outer end of this lever 45 is a spring cup 39 having a threaded shank 40 adapted to a threaded aperture 41 in the arm 38, a lock nut 42 being provided to secure the cup 39 in its adjusted position. A fixed spring cup 43 is formed in the upper 50 face of one of the projections 15, and a compression spring 44 is adapted to be maintained within and between the cups 39 and 43. By adjusting the cup 39 with respect to the lever 38 and the cup 43, the amount of 55 compression on and consequently the force exerted by the spring 44 may be varied.

As illustrated in Figs. 1, 2 and 3 of the drawing, the driving chain 8 moves the carriage 1 with the engaged wire 6 outwardly 60 in the direction of the arrow shown in Fig. 2, and as the carriage approaches the end of its outward cycle of reciprocity the curved end of the release dog 20 engages the roller 25. Continued motion of the carriage by 65 the chain 8 causes the cam face 24 of the re-

lease dog 20 to ride up on the roller 25 against the tension exerted by the spring 22. The first part of the movement of the dog 20 over the roller 25 causes the end 18 of the retaining lever 16 to move out of the cavity 19 in the driving latch 13, as illustrated in full lines in Fig. 3.

When the end 18 of the lever 16 is free of the cavity 19, and resistance to the outward movement of the carriage is produced by the dog 20 engaging the roller 25, the shoulder 12 of the lever 13 is forced out of engagement with the projection 11 of the chain 8, the chain 8 being continuously driven. After the release of the shoulder 12 from engagement with the projection 11, the carriage continues to move outward by virtue of its developed momentum, and in order to prevent a sudden and hammer-like pounding of the carriage 1 against the fixed 85 abutment 28 the cam face 24 of the dog 20 is adapted to ride up upon the roller 25 thereby increasing the tension of the spring 22 and the subsequent resistance to the movement of the carriage, which damps the 90 movement of the carriage, and which, under ordinary conditions, is sufficient to cause the carriage to come to a complete stop before engaging the said fixed abutment. However, such engagement is effectively prevented in a 95 manner illustrated by broken lines on Fig. 3 wherein the retaining lever 16 is shown as being turned on its pivot until the flat side thereof engages the body portion 2 of the carriage 1, and the crook portion of the dog 20 engages the roller 25, as illustrated in said figure.

As shown in Figs. 4 and 5, the dampening of the outward movement of the carriage is effected by co-operative engagement between 105 the dog 20^a and the cam face 37 of the projection 27^a against the counter-action of the spring 44.

Having described in detail two embodiments of my invention, other modifications 110 thereof will obviously present themselves to those familiar with mechanical arts. Therefore, only such limitations should be placed upon the scope of my invention as are prescribed by the appended claims or dictated 115 by the prior art of record.

I claim:

1. In a pile wire controlling mechanism comprising a rail, a wire controlling carriage adapted to be reciprocated on said rail, a chain for moving the carriage in one direction, a driving latch pivotally mounted on the carriage and adapted to engage the chain, and a retaining lever pivotally mounted on said carriage and adapted to engage the driving latch, the combination of a release dog rigidly attached to said retaining lever, a projection on the rail, a cam path formed on one of said elements and adapted to be engaged by the other of said 120 125 130

elements, and resilient means opposing the pivotal movement of said release dog for dampening the developed momentum of the carriage.

- 5 2. In a pile wire controlling mechanism comprising a rail, a wire controlling carriage adapted to be reciprocated on said rail, a chain for moving the carriage in one direction, a driving latch pivotally mounted on the carriage and adapted to engage the chain, and a retaining lever pivotally mounted on said carriage and adapted to engage the driving latch, the combination of a release dog rigidly attached to said retaining lever, a projection on the rail, a cam path formed on one of said elements and adapted to be engaged by the other of said elements, and means for dampening the developed momentum of the carriage comprising a resilient element adapted to oppose the pivotal movement of the release dog for increasing the resistance offered to the movement of the carriage on the rail, after its release from the driving chain, in proportion to the extent of the relative movement of the release dog on the said projection.
3. In a pile wire controlling mechanism comprising a rail, a wire controlling carriage adapted to be reciprocated on said rail, a chain for moving the carriage in one direction, a driving latch pivotally mounted on the carriage and adapted to engage the chain, and a retaining lever pivotally mounted on said carriage and adapted to engage the driving latch, the combination of a release dog rigidly attached to said retaining lever, a projection on the rail, a cam path formed on one of said elements and adapted to be engaged by the other of said elements, and means for dampening the developed momentum of the carriage comprising a spring extending between said release dog and said carriage.
4. In combination with pile wire controlling mechanism comprising a rail, a wire controlling carriage adapted to be reciprocated on said rail and a chain for moving the carriage in one direction; a driving latch pivotally mounted on said carriage for movement in a plane coincident with the plane of movement of said chain and adapted to engage said chain; a retaining lever pivotally mounted in said carriage and movable in a plane coincident with the plane of movement of said driving latch and adapted to engage said driving latch; a release dog formed integral with said retaining lever, a projection on said rail; a cam face formed on said release dog adapted to be engaged by said projection, and a tension spring having one end secured to the outer end of said release dog and its opposite end secured to the said carriage for producing a dampening effect to counteract the developed momentum of said carriage.
5. In combination with pile wire controlling mechanism comprising a rail, a wire controlling carriage adapted to be reciprocated on said rail and a chain for moving the carriage in one direction; a driving latch pivotally mounted on said carriage for movement in a plane coincident with the plane of movement of said chain and adapted to engage said chain; a retaining lever pivotally mounted in said carriage and movable in a plane coincident with the plane of movement of said driving latch and adapted to engage said driving latch; a release dog formed integral with said retaining lever, a projection on said rail; a cam face formed on said release dog adapted to be engaged by said projection, and a tension spring having one end secured to the outer end of said release dog and its opposite end secured to the said carriage for producing a dampening effect to counteract the developed momentum of said carriage.

WILLIAM E. SMITH.
